UNITED STATES PATENT OFFICE.

HERMAN EGLI, OF WEST HOBOKEN, NEW JERSEY.

ARTIFICIAL LIMB.

1,201,812.

Specification of Letters Patent. Patented Oct. 17, 1916.

Application filed February 24, 1916. Serial No. 80,113.

REISSUED

To all whom it may concern:

Be it known that I, HERMAN EGLI, a citizen of the United States, and resident of West Hoboken, in the county of Hudson and 5 State of New Jersey, have invented an Improved Artificial Limb, of which the following is a specification.

Modern artificial limbs must combine lightness, strength and durability and, for 10 those reasons, were heretofore made of wood, aluminum, rawhide and similar material. In some cases they were shaped out of sheets of comparatively thin material, in other cases, they were built up of layers of 15 strips of such material, the strips of one layer angularly disposed in relation to the strips of the adjoining layer.

The artificial limb, illustrated in the accompanying drawing, is formed of one continuous strip of sheet material and obtains 20 its final shape, mating a natural limb, by cutting the strip similar in form to the letter **S** and arranging it into a helix, having suitable means for securing it to the human 25 body and for attaching the necessary joints.

The limb and its details of construction are shown in Figure 1, as a side elevation 30 of a lower leg. Fig. 2, illustrates one form of the **S** shaped strip of sheet material. Fig. 3, is a diagrammatic view of a device for shaping the strip into a helix. Fig. 4, is a side elevation of the limb with a foot attached. Fig. 5, is a detail of construction of adjoining turns of the helix, and Figs. 35 6 and 7, are details of construction of the means for securing the foot to the limb.

A sheet of fibrous relatively thin material is cut into cyma-form or **S** shaped elements 1, varying in dimensions and curvatures according to the size and form of the natural limb to be imitated. This element or templet is first softened and made pliable by, for instance, steaming or heating it and then shaped by rolling it through a device 40 similar to the one shown in Fig. 3, although any other method or apparatus may be employed for this purpose. The rollers 18,

19 and 20, engaging the templet, may be suitably heated, if desired, so that the material first softened is hardened and stiffened again, after having been shaped. The templet, when leaving the rollers, will at once assume the form of a helix, as shown in Fig. 1, formed by abutting turns 2, 3, 4 and 5, which are secured together by strips of 55 adhesive material 6 and 7, or any other convenient means. The sides of the abutting turns may be flush, edge to edge, or may overlap, as shown. The helix is then coated with one or more layers of varnish, so as to 60 make it moisture-proof and stiff and further provided with a brace 8, having bearings 9, for the kneejoint and a brace 10, preferably integral with the first, having 65 bearings 11, for the foot joint.

The foot may be carried by having the ends of the lower brace 10, pass a bearing plate 13, provided with slots 14 and 15. A bolt, located in the bearing groove 16, of the foot 12, secures the foot to the bearings 70 11. A retractile spring 17, or other well known means, is usually provided for giving the foot the necessary resiliency.

Claims:

1. The method of producing artificial 75 limbs which consists in, first, providing a continuous cyma-form element of fibrous sheet material, second, shaping the same into helicoidal form, and third, securing together the sides of abutting turns of said helix. 80

2. An artificial limb comprising a helix formed of a continuous cyma-form element of fibrous sheet material.

3. An artificial limb comprising a helix 85 formed of a continuous element of fibrous sheet material having the sides of abutting turns of said helix overlapping, and means for securing together said abutting turns.

New York, in the county and State of New York, this 9th day of December, 1915.

HERMAN EGLI.
